UNITED STATES PATENT OFFICE.

ANDREW CAMPBELL, OF BROOKLYN, ASSIGNOR TO JOHN AND EDMUND McLOUGHLIN, OF NEW YORK, N. Y.

SHELL OR COVER FOR PRINTERS' ROLLERS.

SPECIFICATION forming part of Letters Patent No. 294,438, dated March 4, 1884.

Application filed July 30, 1883. (No model.)

To all whom it may concern:

Be it known that I, ANDREW CAMPBELL, a citizen of the United States, residing at Brooklyn, Kings county, New York, have invented 5 certain Improvements in Shells or Covers for Printers' Rollers, of which the following is a specification.

Rollers for the use of printers have been provided with covers of leather. It is to this 10 class of rollers that my present invention relates. Heretofore, so far as I am aware, these leather covers have been stitched into the form of a flexible tube and turned, and then drawn over the yielding elastic core; or it has been 15 proposed to make the core of some substance capable of being melted, and to pour it into said tubular cover while the latter is held in a tubular mold.

My object is to produce a stiff tubular shell- 20 like cover of leather, that may be made and sold as an article of manufacture; and in my construction I also seek to avoid the stitching, which, when the leather wears away, appears at the surface, and to provide a protecting 25 film that will prevent the oils and solvents of the ink from penetrating through the leather to the core and injuring the same. This is quite important when the core is of some substance that will be liable to injury from this 30 cause—as rubber, for example.

In carrying out my invention I take a former, preferably of wood and sectional, in the 35 nature of a cylinder equal in diameter to the core of the roller. On this I wrap a strong fabric, preferably of linen, although muslin or other strong fabric would serve. This wrapping I coat with hot glue, and then apply the leather designed to form the cover of the roller. This leather is cut to the exact size to fit, 40 preferably beveled at the edges to lap a little, and these edges are glued to hold the leather in place. It may be temporarily wrapped exteriorly until the glue sets or hardens. The shell thus formed is then slipped off the former, 45 and is ready to receive the core. The glue imparts sufficient stiffness to the shell to prevent its distortion, and it also, being insoluble in the oils and solvents of the ink, serves to protect the core. The linen or other fabric 50 crosses the joint where the edges of the leather abut, and makes a sufficiently strong joint.

In the drawings, which serve to illustrate my invention, Figure 1 is a longitudinal axial section of my shell constructed in the most approved form, and Fig. 2 is a cross-section of 55 the same. Fig. 3 is a view designed to illustrate the spiral wrapping of the linen or other lining fabric on the former.

A represents the leather covering, the edges of which are by preference made to lap a little, as at *a* in Fig. 2.

B is the linen lining, which I prefer to apply to the former by wrapping it spirally around the same from end to end, as illustrated in Fig. 3.

C is the former, which may be a simple cylinder of wood, or sectional, as preferred.

In order to form a stiffened margin for the shell or tubular cover, I prefer to insert in it at the end a band, *b*, formed, by preference, 70 of several coils or turns of wire. The linen or other lining fabric is folded over the band outwardly and glued. In order that this band shall not, owing to its thickness, produce a ridge by raising up the leather, I chamfer or 75 cut away the latter, as at *c*, so as to leave room for said band.

In applying the band *b* the wire may be wrapped over the lining on the former C, and the margin of the fabric B turned over and 80 glued down on said band.

These shells may be made and sold as an article of manufacture and sale, and they may be applied to their cores in any way desired—as, for example, the shell may be slipped into 85 the ordinary mold, the roller-stock set in place, and the usual roller-composition melted and poured in; or it may be slipped over a rubber or other core.

In order that the leather cover A may be 90 gathered and drawn down to the roller-stock with a draw-string or thong, so as to protect the ends of the composition, I usually allow the leather to extend beyond the band *b*, as shown at the left in Fig. 1. The leather may 95 be cut off even with said band, if it is not desired to employ it for the purpose I have described. It is not new, broadly, to thus draw a leather cover over the end of the cushion and secure it to the stock.

Having thus described my invention, I claim—

1. As a new article of manufacture, a shell to form the cover of a printer's roller, comprising an exterior cover of leather and a lining of linen or other similar material glued to the inside of the said leather, and the whole formed into a cylindrical shell, substantially as set forth.

2. As a new article of manufacture, a shell to form the cover of a printer's roller, comprising an exterior cover of leather, cut away at *c*, an inner lining of linen or other like fabric

glued to the inside of the leather, and the band *b*, secured to the inside of the tubular shell at its end, substantially as set forth.

In witness whereof I have hereunto signed 15 my name in the presence of two subscribing witnesses.

ANDREW CAMPBELL.
